UNITED STATES PATENT OFFICE

THOMAS P. GILSENAN, OF OAKLAND, CALIFORNIA

DESIGN FOR AN ELECTROLIER

Application filed March 20, 1929. Serial No. 30,528. Term of patent 3½ years.

To all whom it may concern:

Be it known that I, THOMAS P. GILSENAN, a citizen of the United States, residing at Oakland, in the county of Alameda and State of California, have invented a new, original, and ornamental Design for Electroliers, of which the following is a specification, reference being had to the accompanying drawing, forming part thereof.

Figure 1 is a front elevation of an elec-

trolier, showing my new design, and wherein the opposite side of said electrolier is identical with the side illustrated.

Fig. 2 is a transverse sectional view taken on the line 2—2 of Fig. 1.

I claim:

The ornamental design for an electrolier as shown.

THOMAS P. GILSENAN.
